DESIGN FOR A SPRAY RIG BODY

Roy M. Magnuson, San Jose, Calif., assignor to
Food Machinery Corporation, San Jose, Calif.,
a corporation of Delaware

Application February 18, 1935, Serial No. 55,478

Term of patent 14 years

To all whom it may concern:

Be it known that I, Roy M. Magnuson, a citizen of the United States and a resident of San Jose, county of Santa Clara, State of California, have invented a new, original, and ornamental Design for a Spray Rig Body, of which the following is a specification, reference being had to the accompanying drawing forming part thereof.

Figure 1 is a perspective view of a spray rig body embodying my new design.

Figure 2 is a plan view thereof drawn to a slightly reduced scale.

Figure 3 is a front elevation thereof also drawn to a slightly reduced scale.

I claim:

The ornamental design for a spray rig body as shown.

ROY M. MAGNUSON.
